UNITED STATES PATENT OFFICE.

STEPHEN W. MAXSON, OF DASSEL, MINNESOTA.

TABLE.

SPECIFICATION forming part of Letters Patent No. 298,601, dated May 13, 1884.

Application filed August 18, 1883. (No model.)

To all whom it may concern:

Be it known that I, STEPHEN W. MAXSON, of Dassel, in the county of Meeker and State of Minnesota, have invented a new and useful 5 Improvement in Tables, of which the following is a specification.

The object of my invention is to provide for adjustment of tables upon uneven floors or on ground not level, so as to support the table 10 firmly and prevent shaking or jostling.

The invention consists in fitting the two legs at one side or end on a rocking bar, by which the level may be changed according to the 15 character of the floor or other surface, as hereinafter described and claimed, reference being had to the accompanying drawings, in which similar letters of reference indicate corresponding parts.

In the drawings, Figure 1 is an end elevation of a table with my improvement, and Fig. 2 is a longitudinal section on line xx of Fig. 1.

The table A is of ordinary construction, except as hereinafter specified, having top a , side and end rails, b , and made with the two 25 legs c at one end of the table attached firmly, as shown in Fig. 2. The two legs c at the opposite end are attached to the ends of a bar, d , and the bar d is pivoted to the end rail, b , at its mid-length by a screw-pin, e , that passes 30 through the rail and through a nut, f , fixed to the inner surface of the rail. On the outer end of the pin e is a knob, g , for use in turn-

ing the screw in tightening or loosening it; but any suitable device may be used in place of the knob. By this construction, the two 35 legs c being attached to the bar d , and the latter pivoted to the end rail, the bar and legs can be rocked transversely of the table, and either corner-leg thus shortened or lengthened to obtain a firm support of the four legs on the 40 floor or on the ground. In this manner the table can be made to set firmly, and when properly adjusted the legs are held by turning the screw inward until the knob clamps the bar d .

This invention can be applied to any four-leg table without adding materially to the expense, and it is especially useful for camp-tables.

The rocking bar d may be made in two pieces 50 or jointed in the middle, each portion carrying a leg, and the clamping device may be made separate from the pivot.

Having thus described my invention, I claim as new and desire to secure by Letters Patent— 55

The pivoted bar d and legs c , fixed to the bar, combined with a table having fixed legs opposite to the side or end where the bar is attached, substantially as described.

S. W. MAXSON.
